UNITED STATES PATENT OFFICE

ANTHONY PETTICORE, OF SEDRO WOOLLEY, WASHINGTON

AUTOMATIC SWITCH ELECTRIC SADIRON

Application filed May 7, 1930. Serial No. 450,418.

My invention relates to improvements in automatic switch electric sad-irons and has for an object to provide an electric sad-iron the electric circuit of which is maintained closed during the normal use of the iron and is automatically opened as soon as use of the iron ceases through the operation of an automatic switch.

Another object of my improvement is to provide an adjustment for said switch whereby it may be maintained closed as long as desired.

Another object of my improvement is to provide an adjustment for said switch whereby the electric circuit may be maintained open during the use of the iron.

Another object of my improvement is to provide protection to the hand grasping the split iron handle during its use.

Other objects of my improvement will appear as the description proceeds.

I attain these and other objects of my improvement with the mechanism illustrated in the two sheets of drawings accompanying this specification, and forming a part thereof, in which Figure 1 is a side elevation of a sad-iron with my improvement in place thereon, Fig. 2 is a front end elevation of the handle of the iron with the remainder thereof broken away, Fig. 3 is a cross section of the handle on the line 3-3 of Fig. 1, and Fig. 4 is a rear end elevation of Fig. 1.

Similar characters refer to similar parts throughout.

Certain parts are broken away to show other parts hidden thereby.

With more particular reference to the designated parts: Sad-iron body 5 has handle shank 6 and handle 7 fastened to the shank by bolt 8 therethrough with nut $\alpha 8$ thereon. Handle 7 has a flat top and represents little more than one-half of the usual handle; the remaining, or upper part 9 being separate from the lower part 7. Fastened on the bottom of upper handle part 9 is flat spring bar 10 and guard plate 13 by rivets 14. Near the front end of spring bar 10 is spring loop 11 terminating in dependent end $\alpha 11$ having an opening therein through

which bolt 8 is extended with nut $\alpha 8$ thereon on clamping spring end $\alpha 11$ firmly against the front end of the handle shank 6. Near the rear end of spring bar 10 is spring loop 12 with end $\alpha 12$ dependent therefrom. Beneath the head of bolt 8 on the rear end thereof is clamped stop clip 15.

The usual connection plug 16 has two halves which are clamped together by bolt 17 therethrough retained by nut $\alpha 17$ thereon. The end $\alpha 12$ of the spring bar has an opening therethrough in which is extended bolt 17 to clamp the spring end between bolt head $\beta 17$ and plug 16.

The plug is provided with the usual spring contact clamps 18, 18 to contact with iron element terminals 19, 19 and complete the electric circuit between the two cables 20, 20 of the connecting cord and the iron in the usual way.

Iron socket 21 is lined by guide strip 22 on the interior of its rear wall to bear against the rear wall of plug 16 when the latter is in operative contact position and also in open-circuit position in plug socket 21.

The upper end of the rear wall of the socket is extended to form bracket $\alpha 21$ in which is fastened horizontal pin 23. On pin 23 is mounted catch loop 24 for oscillation. Loop 24 is disposed to pass over the top of the protruding end of bolt 17 to catch the same and hold plug terminals 18 in electric contact with element terminals 19. Also loop 24 may be disengaged from the bolt end by turning the same backward on pin 23 and it may occupy its dotted position at 24' out of engagement with the bolt.

When loop 24 is disengaged from bolt 17 spring loop 11 reacts and moves the rear end of top handle part 9 to its dotted position at 9' when further upward movement thereof is stopped by the bearing of bolt head $\beta 17$ in its dotted position at $\beta 17'$ on stop clip 15 as shown in Fig. 1. Then contact clamps 18 are at 18' out of contact with element terminals 19 and the circuit through the cord and iron element is open.

The dependent flanges $\alpha 13$, $\alpha 13$ are shaped to fit the contour of the handle 7 and serve to cover the opening between the lower and 100

upper parts of the handle when the latter is at 9' and thus prevent the flesh of the operator's hand from entering this opening to be pinched when the part 9 is carried down to 5 contact with part 7.

In operation: It is assumed that cables 20, 20 of the cord are connected with a source of electricity, not shown. Then with the operative parts of the iron in the positions illustrated in full lines the electric elements, not shown, with which terminals 19, 19 are connected in the iron, are heated and the iron is ready for use. This is the same condition which pertains when the usual electric sad- 10 iron is connected with the service current by inserting the plug 16. Use of the iron may proceed, but, if it is desired to take advantage of the protection provided by my automatic switch, loop 24 is turned down to its position 15 at 24' and the divided parts of the handle are retained in adjacent relation by the grasp of the user's hand thus continuing electric contact of terminals 19 and clamps 18 during use. But when use ceases and the hand of the 20 operative releases its grasp of the handle the upper part 9 thereof is carried to its position at 9' by the reaction of spring loop 11 and contact between terminals 19 and clamps 18 is broken and the electric current through the 25 iron is interrupted thus automatically saving the fabric from injury on which the iron may have been allowed to remain by the operative. 30

At times during use of the electric iron it becomes too hot and it is desired to open the 35 circuit therethrough and continue to use the iron. This is attained by turning catch loop 24 back to its full-line position after bolt 17 has moved to its position at 17' when the bolt will bear on top of the loop and the plug will 40 be retained in its position at 16' with terminals 18 and 19 out of contact and the circuit through the iron open. The iron may thus be continued in use till it is desired to again turn on the current when loop 24 is turned 45 back and the two parts of the handle again are brought together by the hand grasp of the user and thus the electric circuit through the iron is again established.

It now may be apparent that my automatic 50 electric switch and the controls provided therefor very well serve the purposes for which they are designed and afford convenient safety not found in the ordinary electric sad-iron.

The purpose of the guide 22 in socket 21 is to retain the lower end of plug 16 in rectilinear reciprocation during the circuit making and breaking movements thereof. Upper 55 handle part 9 oscillates about the center of spring loop 11 which would carry the lower end of the plug outward during the upward movement of handle 9 and thus prevent the proper alignment of clamps 18 and terminals 60 19 for reengagement. Spring loop 12 pro-

vides the needed freedom for oscillation between plug 16 and spring bar 10.

Having thus disclosed my invention, what I claim as new therein and desire to secure by Letters Patent is,—

An electric sad iron including a sad iron base, an electric heating element within said base, front and rear handle shanks fastened to said base projected upward therefrom, the bottom part of a sad iron handle fastened to the tops of said handle shanks, the top part of said handle disposed on top of said bottom part thereof, a spring fastened to the front end of said top handle part and to said front handle shank mounting thereby said top handle part for oscillation and tending to separate the said handle parts at the rear ends thereof, an intervening plate fastened to the bottom surface of said top handle part having its edges bent downward adjacent the sides of said bottom handle part covering the opening therebetween when said handle parts are separated by said spring reaction, heating element terminals projected upward from said base, and an electric contact plug fastened to the rear end of said top handle part disposed for making electric connections with said heating element terminals when said top handle part is turned down against said spring reaction and for breaking said connections when said top handle part oscillates upward under said spring reaction.
